J. E. WHEELER

MANUFACTURE OF CORNER ANGLES OF ROOF GUTTERS

Filed Jan. 2, 1926

Patented Jan. 24, 1928.

UNITED STATES PATENT OFFICE.

JOHN EDWARD WHEELER, OF DUNEDIN, NEW ZEALAND.

MANUFACTURE OF CORNER ANGLES OF ROOF GUTTERS.

Application filed January 2, 1926, Serial No. 78,982, and in Australia January 13, 1925.

This invention relates to improvements in corner angles of roof gutters made from sheet metal and is directed to the provision of corner angles of gutters formed with vertical inner walls, a flat bottom and curved outer walls.

In affixing sheet metal gutters of the above mentioned type to the roofs of buildings, it is at present customary to form the corners by "mitring" that is by cutting the gutters obliquely upon a line bisecting the angle to be negotiated and then soldering or otherwise fastening the two said parts together. This operation is generally performed by the plumber erecting the gutter and involves skilled workmanship to provide a neat appearance and, at the same time, ensure a strong and water-tight joint. In effecting circular bends in the above type of gutter it is the usual practice to form the same by joining together several gusset shaped pieces of gutter, each of which has to be cut very accurately in order to ensure symmetry of curvature at the bend, and which are, therefore, relatively costly to manufacture.

I am aware that it has been proposed to stamp corner angles for gutters in one piece but whilst this can be accomplished more or less satisfactorily when the gutter is of a comparatively shallow concavo-convex or more or less regularly curved formation it is not commercially practicable when the gutters are provided with a vertical inner wall and are relatively deep in cross section.

Now the object of the present invention is to provide means whereby corner angles of roof gutters or other sheet metal gutters having vertical inner walls may be manufactured economically to conform to the particular corner to be negotiated, avoiding the sharp angular structures and the joints therein as at present adopted, whilst, at the same time, enabling them to be produced in quantity in a factory and used ready-made on a building, thus effecting a considerable saving of time and labour in affixing the gutters.

I accomplish the above mentioned object by forming corner angles made from a plurality of angle shaped-metal blanks the parts comprising an outer wall (curved in plan) to compass the required angle and shaped in cross section to the required pattern and design, an inner vertical wall bent to the required angle, and a flat bottom, the parts having their contiguous edges connected together so that the corner angle formed there-

by will be substantially of the same size and shape in cross section as the lengths of gutters to be connected thereby.

In order that the invention may be better understood reference will now be had to the accompanying sheet of drawings wherein one method is illustrated of giving effect to this invention.

Figure 1 is a view in plan of portion of a roof provided with a gutter having the corner angles thereof constructed and arranged in accordance with the present invention.

Figure 2 is a view in plan (drawn to a larger scale) of the corner for a salient angle shown in Figure 1.

Figure 3 is a view in sectional elevation of the corner angle taken on the dotted line 3-3 of Figure 2.

Figure 4 is a view in perspective of portions of the corner angle shown in Figures 2 and 3 and illustrates a stage in the manufacture thereof.

Figure 5 is a view similar to Figure 3 and shows a modification of the invention.

Figure 6 is a view in plan of a corner for a re-entrant angle as shown in Figure 1 and drawn to a larger scale.

Figure 7 is a view in sectional elevation of the corner angle taken on the dotted line 7-7 of Figure 6.

Figure 8 is a view in perspective of the inner wall and bottom portion of the corner angle shown in Figure 6 and illustrates a stage in the construction thereof.

Figure 9 is a view in sectional elevation taken on the dotted line 9-9 of Figure 6.

Referring to Figure 1 of the drawings, *a* represents a portion of a roof (in plan) provided at its outer and lower edges with a gutter which is connected thereto in any appropriate manner.

The straight lengths of gutter *b* are connected by corner angles, formed of a plurality of angle shaped parts made from blanks of sheet metal and shaped by means of suitable dies or presses.

Each of these corner angles may comprise three separately formed parts, namely, an outer wall *c*, an inner wall *d* and bottom *e* conveniently joined together along their contiguous longitudinal edges; or the bottom *e* may be integral with the outer wall *d* (Figure 5); or the bottom *e* may be integral with the inner wall *c* (Figure 7).

The formation of a salient angle by one adaptation of this invention is shown in

Figures 2 and 3. In these views the outer wall *c* is shaped as a convex curve (as shown at *c*¹ Figure 1) by suitable dies and presses preferably in two forming operations from a blank of approved shape to conform to the cross section of the corresponding parts of a length of spouting. In the first operation a fold *c*² is formed along the bottom edge and the rest of the 10 section excepting the upper portion is shaped to the desired configuration as indicated in Figure 3 of the drawings. In the second operation the upper portion is bent over to complete the formation of a bead *c*³ which 15 conforms in shape to a bead on the gutter wall of the straight lengths of the gutter.

If desired the procedure may be reversed and the bead *c*³ and outer wall completed in the first forming operation, the fold *c*² 20 being then formed in a succeeding operation.

The formation of the outer wall *c* to the shape shown in Figure 3 has been found to be a simple operation by following the 25 methods usually employed in the stamping and pressing of sheet metal by dies and presses.

The inner wall *d* is formed from a blank of sheet metal being bent to an angle of the 30 required degree to suit the position where it is to be affixed and a fold *d*¹ is formed at the bottom edge thereof in any well known way.

In like manner the bottom piece *e* is 35 formed from a blank of sheet metal shaped to conform to the desired angle and a flange *e*¹ is turned downwardly on the inner edge thereof and another flange *e*² is turned upwardly on the outer edge thereof (see Figure 4).

The flange *e*² of the bottom piece *e* is 40 adapted to correspond with and be accommodated by the fold *c*² of the outer wall and likewise the flange *e*¹ of the said bottom *e* is adapted to correspond with and be engaged by the fold *d*¹ formed on the lower portion of the inner wall.

The members are then rigidly connected 45 one to the other by a seam closing press or the like, the joining of the folds *c*² and *e*² forming one longitudinal seam and the joining of the folds *d*¹ and *e*¹ forming another longitudinal seam.

In the case of a re-entrant angle the outer 50 wall *c* is shaped to a concave curve as shown at *c*⁴ in Figure 1 and preferably in two operations as above described, in connection with the formation of a salient angle. Instead of forming the angle of three separate blanks as previously described with 55 regard to a salient angle, in the case of a re-entrant angle it is preferably made of two parts as shown in Figures 6, 8 and 9.

The inner wall *d* and bottom *e* in this 60 case are shaped by simultaneously bending

and plaiting the metal blank to produce the requisite angular form, the plaited portion *e*³ of the bottom *e* being pressed flat to enable a satisfactory junction to be made with the outer part of the corner angle (see 70 Figures 6, 8 and 9).

The corner angle is then completed by attaching the outer wall *c* to the edge of the bottom *e* by a seam joint as hereinbefore described.

Figure 8 shows a stage in the plaiting operation of the bottom *e* formed integrally with the inner wall *d* and it will be understood that in this construction the danger of leakage is avoided.

It will be understood that the parts forming the corner angle may be joined together in any well known manner instead of seaming as shown, such as by welding, riveting, soldering or any other means.

The portions of a corner angle may be galvanized before they are joined together or alternatively they may be galvanized after they have been so joined, and, in practice, we find the latter procedure more desirable as water-tight joints and seams are thereby ensured.

If preferred the outer wall *c* and the bottom *e* of a corner angle can be formed integrally and in this case the inner edge of 95 the bottom can be formed with downwardly projecting flange *e*¹ adapted to be seam folded to the bottom edge of the inner wall *d*¹ (see Figure 5). The inner wall in this instance can be shaped with a flange *d*¹ on 100 its lower edge.

Although right angle corners having the inner sides thereof bent sharply at 90° are illustrated in the drawings, it will be obvious that the invention may be applied 105 with equal facility to corner angles which are greater or less than a right angle and which may have the inner angles rounded. Moreover, the curvature of the outer walls (in plan) of the corner angles can be varied 110 as desired to permit of a free flow of water around corners of gutters.

Corner angles for roof gutters constructed in accordance with the invention can be manufactured economically, will be neat in 115 appearance, and can be readily connected to lengths of gutters in the ordinary way when the same are being applied to buildings in course of erection.

I claim:—

1. A corner angle for roof gutters of the kind described having a vertical inner wall, a flat bottom and a curved outer wall, comprising a plurality of separately formed angle shaped pieces of sheet metal joined 125 along their longitudinal edges to conform in shape to the cross section of a roof gutter.

2. A corner angle for roof gutters of the kind described having a vertical inner wall, a flat bottom and a curved outer wall, coin- 130

prising a plurality of separately formed angle shaped parts of sheet metal having their longitudinal edges connected to each other, the outer wall portion of the corner angle being curved (in plan) and the inner vertical wall portion being bent to the angle to be negotiated by the corner.

3. A corner angle for roof gutters of the kind described having a vertical inner wall, a flat bottom, and a curved outer wall, comprising separately formed inner and outer wall parts and a bottom part, the inner part being disposed vertically, the bottom part horizontally, and the outer part having a curved formation in plan, said parts having their longitudinal edges connected together.

4. A corner angle for roof gutters of the kind described, comprising a plurality of parts formed from sheet metal blanks, said parts comprising respectively, an outer wall curved in plan to encompass the required angle, a vertical inner-wall bent to the angle required, and a flat bottom, the contiguous edges of the said parts being connected together.

5. A salient corner angle for roof gutters of the kind described made of a plurality of angle shaped parts formed from sheet

metal blanks, and comprising respectively, an outer wall of convex formation, an inner vertical wall bent to the angle required, and a flat bottom, the contiguous edges of the said parts being connected together in such manner that a cross section of any part of the corner angle conforms to the cross section of the lengths of gutters adapted to be joined by the corner angle.

6. A corner angle for roof gutters of the kind described formed of an outer section of sheet metal shaped to the curve required in plan and of cross section to the pattern or design required, a fold along the bottom edge of the outer section, an inner vertical section of sheet metal bent to a sharp angle of the degree required, a fold along the bottom edge of the inner vertical section, a flat bottom section of sheet metal of the shape required to unite the said sections, and folds along both the edges of the bottom section, the said sections being united together by forming seams along the folds on the contiguous edges thereof, substantially as described.

In witness whereof I hereunto affix my signature.

JOHN EDWARD WHEELER.
